MOUNTING STRAP

George P. Wakefield, Vermilion, Ohio, assignor to
 The F. W. Wakefield Brass Company, Vermilion, Ohio, a corporation

Application December 7, 1946, Serial No. 714,767

7 Claims. (Cl. 248—343)

1

This invention relates to mountings for securing luminaires and the like to ceilings and particularly to a new and improved adjustable mounting strap.

One of the principal objects of the present invention is to provide a mounting which when secured by securing means which are fixed relative to the ceiling, is capable of universal bodily adjustment parallel to the plane of a ceiling.

Another object is to provide an adjustable mounting strap to which the stem of a luminaire may be effectively and readily attached so as to depend therefrom, and relative to which the stem may be rotated independently of the change of position of the strap.

Another object is to provide a supporting body and means thereon adapted to be connected to and to support a luminaire in depending relation to the body and a toggle means connected to the body for supporting the body from the ceiling for limited universal adjustment parallel to the plane of the ceiling.

Other objects and advantages will become apparent in the following description wherein reference is made to the drawings, in which:

Figure 1 is a side elevation of a luminaire showing in general the manner in which it is supported from the ceiling;

Figure 2 is a perspective view of a mounting strap embodying the principles of the present invention and showing the manner of securing the same on the ceiling and the manner in which the luminaire is supported thereby;

Figure 3 and Figure 4 are a top plan view and a side elevation, respectively, of the mounting strap illustrated in Figure 2;

Figures 5 and 6 are a top plan view and side elevation, respectively, of a modified form of mounting strap.

Referring first to Figure 1, there is illustrated a luminaire unit 1, having a body in the form of a shell of translucent material which is elongated parallel to the ceiling and within which are disposed suitable illuminating means, not shown. Generally, in these structures, the illuminating means comprise elongated tubular fluorescent lamps, and consequently the luminaires are quite long parallel to the plane of the ceiling. Frequently they extend substantially the full width of the room and employ a plurality of fluorescent lamps arranged in a row. Because of their longitudinal extent it is usually necessary to support them at a plurality of points along the length and this is done by means of stems 3 which are arranged in a row and spaced

2

apart from each other uniformly in the row. The stems are connected at their lower ends to the luminaires and extend upwardly therefrom and are connected at their upper ends to the ceiling.

5 The fluorescent lamps whether disposed within the body 2 or thereabove usually extend between sockets which are carried in fixed position on the supporting stems and suitable canopies 4 are carried on the stems and serve to conceal the fastenings of the stems to the ceiling. It is apparent that with plurality of elongated tubular lamps thus arranged in a row and carried in sockets on stems that the stems must be spaced apart from each other with a fairly high degree of accuracy and they must be accurately aligned in the row.

The present invention is concerned primarily with an improved mounting or strap adapted to be fastened to the ceiling and to the stems of the lamps for suspending the stems in accurately spaced relation from each other parallel to the plane of the ceiling and in accurate alignment with each other in rows. Usually luminaires

20 are installed as replacements for existing lighting fixtures and the existing lighting fixtures generally are connected to and depend from electric outlet boxes 5 which are secured in fixed relation to the ceiling. Accordingly, when these fixtures are replaced by luminaires the fluorescent lamps

25 are made of such length that the supporting stems 3 can be spaced apart the same distance as the existing outlet boxes so that the stems can be connected thereto respectively. However, for ordinary separate lighting fixtures the outlet boxes

30 are very often not positioned sufficiently accurately in alignment in a row or spaced sufficiently accurately from each other to fit the rather accurately spaced stems of the luminaire. Furthermore, in new installations it is often difficult to 35 locate the outlet boxes sufficiently accurately in alignment and in spacing from each other to meet the requirements for luminaires.

In order to provide for proper alignment and spacing of the stems 3 when they are to be suspended from such outlet boxes, it is necessary that adjustment of the position of the stems 3 parallel to the plane of the ceiling and laterally and longitudinally of the row be provided for. Therefore, it is necessary that any mounting se- 45 cured to a fixed supporting means on the ceiling, such as the outlet boxes, for supporting the stems be capable of limited universal adjustment relative to the outlet boxes or fixed supporting means in all directions in a plane parallel to the

50 plane of the ceiling.

For this purpose the mounting or strap illustrated in Figures 3 and 4 is provided. In the form illustrated in Figures 3 and 4, the mounting, indicated generally at 6, comprises a single strap of rigid material, such as metal, having a central or mid portion 7 which is offset bodily from the plane of the strap and is connected to the end portions 8 thereof by side wall portions 9. One of the side wall portions 9 is provided with a laterally elongated slot 10 which, at its bottom, connects with a slot 11. The slot 11, in turn, extends to the bottom of the side wall 9 and continues uninterruptedly to the central portion of the mid portion 7, thus forming a slot for receiving a sabre type connection provided on the end of the stem 3 to be associated therewith.

Mounted on the end portions 8, respectively, are links 12 which are pivotally connected by pivots 13 to the end portions 8, respectively, so as to swing freely parallel to the plane of the end portions. Each of the links 12 is provided with an elongated slot 14 which extends from the top to the bottom thereof and preferably radially from the pivotal axis of the pivot 13. The slots 14 are adapted to receive bolts, screws or other suitable suspending elements, as indicated, which may be secured in fixed relation to the ceiling, for example, by screwing them in the usual holes provided at the edges of the outlet boxes 5. Thus when the supporting bolts are fixed in mounting position in the ceiling or outlet box, movement of the strap parallel to the plane of the ceiling is provided by the combined relative lineal movement of the supporting screws in the slots 14, their rotary movement therein, and the swinging movement of the links 12 about their pivotal axes 13. Thus a toggle connection is provided between the supporting bolts and the strap which permits bodily universal movement of the strap parallel to the plane of the ceiling without rotation of the strap about an upright central axis. Accordingly, a plurality of the straps can be mounted approximately in position on the ceiling by connecting them to the existing outlet boxes, and then adjusted to place them both the proper distance apart lengthwise of the row and in proper alignment in the row so that each can engage its respective stem 3 without flexure or warping of the stems or of the body 2 or any other portion of the luminaire 1.

It should be noted that the bolts secured in the slots 14 and into the ceiling or outlet box intersect the plane of the strap. Accordingly, suitable openings 16 are provided in overlying relation to the links 12 so as to afford passage of the bolt through the strap without interference by the bolts with the lateral movement of the strap.

In some instances it is necessary to support the strap from a single bolt in which case the strap illustrated in Figures 5 and 6 is provided. In this form the strap, indicated generally at 29, is the same as the strap above described. Instead of the links 12 however, a supplemental strap 21 overlies the strap 20 and is secured thereto at its ends by means of suitable screws or bolts 22. The strap 21 is provided with a central opening 23 which overlies the central portion of the strap 20. Between the central portion of the strap 21 and the central portion of the strap 20, a link 24, similar to the link 12 above described, is disposed and pivotally secured to the strap 21 by a suitable pivot 25. The link 24 is provided with a bolt receiving slot 26 which is similar to the slot 14 above described. Thus by means of a single bolt passing through the slot 26 and anchored in the

ceiling, the strap 20 is mounted for limited universal bodily movement in all directions which are parallel to the plane of the ceiling. It also may be rotated independently of the bodily movement about the axis of the supporting bolt.

In both forms of the invention, the stems 3 are rotatably supported in the slots of the central portion of the strap, such as the slot 11 in Figure 3, so that adjustment may be made parallel to the plane of the ceiling without interfering with the relatively rotated positions of the stems 3 about their own upright axes, respectively.

This cooperative relation is necessary as the sockets on adjacent stems and which engage opposite ends of the same fluorescent lamp must remain coaxial.

As a result, the straps may be fastened to the outlet boxes, and then adjusted to support the luminaire in the proper position.

Other modes of applying the principle of the invention may be employed, change being made as regards the details described, provided the features stated in any of the following claims or the equivalent of such be employed.

25 I claim:

1. A luminaire support comprising a body adapted to be secured to a fixed supporting means in a ceiling by means of a supporting bolt means extending downwardly from the supporting means, means on said body for connection to a luminaire to support the latter in depending relation to said body, said body being formed with an opening therethrough through which the bolt means is adapted to extend, such opening being of a size and shape to permit substantial universal adjustment of said body in any direction in a plane parallel to the ceiling with respect to the supporting means and bolt means, and a member extending across such opening and underlying said body and adapted to be engaged by the bolt means to frictionally clamp said body in desired adjusted position, said member being movably secured to said body in a plane parallel to the ceiling and providing with such bolt means the aforesaid universally adjustable connection of said body to the ceiling.

2. A luminaire support comprising a body adapted to be secured to a fixed supporting means in a ceiling by means of a pair of supporting bolt means extending downwardly from the supporting means, means on a central portion of said body for connection to a luminaire to support the latter in depending relation to said body, said body being formed with an opening through each of its opposite ends through which the bolt means are respectively adapted to extend, such openings being so spaced apart and each being of a size and shape to permit substantial universal adjustment of said body in any direction in a plane parallel to the ceiling with respect to the supporting means and bolt means, and a pair of members extending across the respective openings and underlying said body and adapted to be engaged by the respective bolt means to frictionally clamp said body in desired adjusted position, each of said members being movably secured to said body in a plane parallel to the ceiling and providing with such bolt means the aforesaid universally adjustable connection of said body to the ceiling.

3. A luminaire support comprising a body, means thereon adapted for connection to a luminaire to support the latter in depending relation to the body, a pair of link members pivotally connected to said body at spaced points for swinging

movement about axes which are upright when said body is in operating position, each of said link members being formed with an elongated slot therethrough offset endwise from and extending lengthwise generally radially from its pivot axis.

4. An adjustable support for a luminaire and comprising a metal strap having a portion centrally thereof offset from its general plane, said portion being adapted for detachably supporting a luminaire, links pivotally secured on one face of the strap at opposite ends thereof, respectively, for swinging movement parallel to said face, and each of said links having a slot extending therethrough in a direction normal to said face and each slot being elongated in a direction parallel to said face.

5. A luminaire support comprising a rigid strap having end portions adapted to be generally parallel to the plane of a ceiling and a central portion offset downwardly from the plane of the end portions, said offset portion having a transverse slot extending through one of its side walls and a narrower slot in said side wall connecting with the bottom of the transverse slot, whereby a luminaire part can be inserted through the slots and lowered after insertion for retention in the narrower slot and against lateral displacement, linkage means connected to the body for swinging movement relative thereto parallel to the plane of the end portions, and securing means on the linkage means arranged for connection to a fixed supporting means for adjustment parallel to said plane of the end portions.

6. An adjustable hanger for a luminaire com-

prising a strap of rigid material having a portion between its ends offset from the general plane thereof, means on the central portion for connection to a luminaire, links pivotally secured to the strap at opposite ends of the central portion, respectively, for swinging movement in the plane of the ends to different positions, and each of said links having a slot extending therethrough normal to the plane of the said ends and elongated parallel to said plane, and each of said end portions having an opening therethrough sufficiently large to afford relative passage of a bolt through the slot of the associated link in each of said different positions.

15 7. A luminaire support comprising a body, means thereon adapted for connection to a luminaire to support a luminaire in depending relation to the body, a link member pivotally connected to the body for swinging movement about an axis which is upright when the body is in operating position, and an elongated slot extending through the link member from top to bottom and being offset endwise from and extending lengthwise generally radially from said axis.
